UNITED STATES PATENT OFFICE.

EDWARD HALL FAILE, OF LARCHMONT MANOR, NEW YORK.

INNER LINING FOR PNEUMATIC TIRES.

1,269,693.

Specification of Letters Patent. Patented June 18, 1918.

Application filed November 5, 1915. Serial No. 59,763.

To all whom it may concern:

Be it known that I, EDWARD HALL FAILE, a citizen of the United States, and a resident of Larchmont Manor, in the county of 5 Westchester and State of New York, have invented certain new and useful Improvements in Inner Linings for Pneumatic Tires, of which the following is a specification.

10 This invention relates to certain improvements in inner-linings for pneumatic tires and has for its object the reduction or elimination of the large number of blow-outs and punctures which commonly occur in pneumatic tires as the latter are at present constructed.

In the ordinary type of pneumatic tire, there is employed an inner tube and an outer casing or shoe which latter is formed 20 of a mass of rubber composition and one or more layers of canvas or other similar material. One of the chief functions of the rubber composition is to furnish the wearing surface of the tire, while the fabric furnishes the necessary strength to resist the 25 expanding force of the compressed gas in the tube. The tube itself is elastic and when inflated presses against all portions of the inner surface of the casing.

30 I have found from experience that a large percentage of the failures and collapse of pneumatic tires are caused by what is known in the trade as either "blow-outs" or punctures. Blow-outs are caused by the 35 expansive force of the compressed gas in the inner tube being greater than the resisting force of the shoe and inner tube, so that the shoe is ruptured and a portion of the inner tube is forced through the rupture until it 40 also ruptures and permits the escape of the compressed gas. This condition generally arises as the result of a weak place in the shoe caused by original defects in manufacture, wear, cuts, etc. If one particular part

45 of one or more of the layers of fabric in the shoe is weaker than the remaining portion, due to original defects, cuts, wear, or other causes, the tendency will be for the adjacent layers of fabric to decrease in strength more 50 rapidly near the weak place than at other points. This is due to the fact that the bending or relative motion of the parts of the tire during use will be greatest at the weakest points, and, since the layers of fabric are bonded or held firmly together, this 55 greater relative motion or bending, will be

transmitted to all of the layers of the fabric near the weak place and will eventually result in their more rapid decrease in strength and rupture than at other points. A cut or 60 break in the composition itself, even though it does not extend in to a sufficient distance to expose the fabric, will permit the shoe to bend at this particular point more easily than at others, and thus the weakness in the 65 fabric, due to repeated bending, will develop more rapidly than at other points.

Failures of tires, due to what is commonly known in the trade as punctures, are generally of two kinds. That is, they are either 70 due to holes being made in the inner tube by nails or other hard pieces of material being driven directly from the outside of the shoe through the wall of the shoe and the tube, and being of sufficient length to extend from 75 the outside surface of the shoe into the inner tube, or, by hard pieces of material being picked up by the shoe and gradually working their way through the wall during the use of the tire and eventually making a hole 80 in the inner tube.

It is primarily to prevent or reduce the possibility of the above mentioned types of punctures and blow-outs that I have designed my improved inner-lining. My improved inner-lining may be manufactured 85 and sold as a separate article of manufacture and adapted to be placed within tires of various different makes already on the market, or the inner-lining may be incorporated in and sold as an integral part of a particular tire. Various changes may be made in the shape, size and materials employed without departing from the spirit of my invention and be within its scope as hereinafter defined.

Reference is to be had to the accompanying drawings in which similar reference characters indicate corresponding parts and which show one construction embodying my 90 invention. In these drawings,

Figure 1 is a transverse section through a portion of a pneumatic tire as commonly constructed and having my improved form of inner-lining in place; and

Fig. 2 is a longitudinal section on the line 2-2 of Fig. 1.

My improved inner-lining includes as essential features, both a layer of pliable and easily penetrable material containing voids 110 and air spaces, and a lining of tough, strong, substantially non-stretchable material which

has greater resistance to penetration, such for instance as canvas, duck, or other material having qualities of this character. In the specific form illustrated, I place within 5 the shoe or casing 10, a layer or lining 11^b of easily penetrable material and inside of this is a tough, strong, penetration-resisting lining 12^b, the latter coming in direct contact with the ordinary inflated inner tube 13 10 of the tire. This inner tube when inflated holds the layers 11^b and 12^b in position by pressing them against the shoe. The latter may be secured to the rim 14 of the wheel in any suitable manner which forms no portion 15 of my present invention. The shoe itself also forms no portion of my invention. The shoe is usually made up of one or more layers of canvas or other suitable material 15 and a mass of rubber composition 16, the latter presenting the wearing surface and the former giving the shoe the required strength to resist the expanding force of the gas in the inner tube.

As has been previously pointed out, any 20 weakening in any particular point in the shoe causes the entire wall of the shoe at the point of weakness to bend more easily than at other points, and, due to the fact that all of the elements of the shoe are bonded together, a bending of one incidentally results 25 in the bending of all of the others at this point. In my improved construction, the soft pliable layer 11^b acts to separate or space the tough, strong layer 12^b from the shoe and thus prevents their being bonded 30 together or acting in unison, either as a result of adhesion or the expansive gas in the inner tube holding the two together. The result of this mechanical separation of the 35 layer 12^b from the shoe 10 is to prevent or greatly decrease the bending or motion of the layer 12^b as compared with the shoe in proximity to the weak spots in the shoe during the use of the tire, and thus to prevent 40 the excessive decrease in strength of the layer 12^b which would otherwise occur if the layer 12^b were bonded to or in direct contact with the shoe itself.

One of the functions of the layer 12^b is to 45 resist the expansive action of the compressed gas in the inner tube and since excessive decrease in strength in the layer 12^b in proximity to weak places in the shoe is prevented by the presence of the layer 11^b, the layer 50 12^b is better able to perform its function. By this novel combination of layers I thus prevent or greatly decrease the possibility of blow-outs.

As previously stated, a large number of 55 punctures are caused by nails or other hard objects being driven through the shoe 10 and into the inner tube 13 and extending from the outside surface of the shoe into the inner tube. I have found from experience 60 that the hard objects causing punctures of

this class do not, as a rule, extend but a short distance beyond the inside surface of the shoe. A second function of the inner lining is to keep the inner tube 13 at a distance from the inside surface of the shoe 70 and thus to prevent the majority of this class of punctures, due to the fact that most of the hard objects driven into the shoe are not long enough to extend through the layers 11^b and 12^b and the inner tube 13. 75

I have shown a nail or tack 23 of a size and length which causes many punctures. It will be noted that the point would extend inwardly beyond the inner tube if the layers 11^b and 12^b were not employed, but with 80 them, the inner tube is spaced a sufficient distance to prevent the point of the object from reaching the inner tube.

A second class of punctures are caused by small hard objects, such for instance as 85 small pieces of glass, which are picked up by the tire during use and gradually work their way through the shoe and inner-tube. With my improved inner-lining, these small hard objects may work their way through the shoe 10 and into the layer 11^b, but are unable to work their way from the soft, pliable, easily penetrated layer 11^b into the tough penetration-resisting layer 12^b. This is due to the fact that the layer 11^b from its 90 nature does not provide sufficient backing to the hard objects for them to force their way into the penetration-resisting layer 12^b and thus they are prevented from puncturing or making a hole in the inner-tube 13. 95 The small hard objects which get into the layer 11^b can work their way about under the rolling and bending action of the tire in use more easily in this layer, due to its quality of being easily penetrable than they 100 can work their way into the tough, strong, penetration-resisting layer 12^b. These hard objects therefore remain in the layer 11^b without causing any damage to the inner-tube. In the drawings, I have illustrated 110 such an object 24, which has worked its way through the shoe but stops in the soft layer without traveling the remaining distance necessary to reach the inner-tube and puncture the latter. My improved inner-lining 115 therefore prevents this second class of punctures. It is of course evident that the layer 11^b should be of such thickness as will be necessary and practical in the securing of the results above referred to. It is also 120 evident that the inner-lining will perform other valuable functions not mentioned above but which will be apparent to a person familiar with the manufacture and use of pneumatic tires.

I have shown the layer 12^b stopping at the points 20 and 21 and thus extending along only a part of the complete circumference of the tube. It would in no way depart from the spirit of my invention if the layer 125 130

12^b were extended to a complete circumference and the opposite edges meet, or if the layer 12^b were still further extended so that its opposite edges would overlap. Similarly I have shown the layer 11^b extending only to the points 18 and 19 and thus of less circumference than the layer 12^b. It would not depart from the spirit of my invention if the layer 11^b were extended around the complete circumference and the edges abutted together or if they were still further extended and the edges overlapped. In ordinary practice, it is not necessary to extend the separate layers of the inner-lining further than is shown in Fig. 2, as most of the punctures and blow-outs occur along the outer peripheral portion of the tire where I place the central portion of these lining layers.

As previously noted, my improved inner-lining made up of two layers may be either manufactured and sold as an article of manufacture and installed by the purchaser or may be incorporated in the tire at the time the latter is manufactured. All portions of the outer surface of the inner-lining may be coated with some sticky or adhesive substance in order that the inner-lining will adhere to the inner surface of the shoe and thus be held in place. This will tend to prevent creeping or shifting of the inner-lining in the shoe during the use of the tire and will prevent the inner-lining from interfering with the removal or insertion of the inner-tube. The fact that all or a part of the outer surface of the lining may more or less adhere to the inner surface of the shoe, does not prevent the easily penetrable pliable portion 11^b from performing its function of separating the inner layer 12^b from the shoe and preventing the formation of a rigid bond therebetween, particularly along the peripheral portion of the tire where wear and liability to rupture is greatest.

As heretofore noted, the layer 11^b might be of suitable rubber composition containing voids or air spaces. The essential features of this lining are that it shall have appreciable thickness, shall be pliable and easily penetrable, and shall not provide sufficient backing to allow small hard objects to work their way through the innermost layer 12^b. The soft layer 11^b shown as molded with air spaces therein to increase its pliability and to decrease its resistance to penetration, or in other words, to decrease the backing or resistance which it might otherwise offer to small hard objects working their way through the shoe and thus to prevent their working their way through the inner layer 12^b. Molding or constructing the inner layer 11^b with air spaces is necessary when it is made of ordinary rubber or rubber composition, particularly if the layers 11^b and 12^b are bonded together, and may be resorted

to as a means of increasing the previously mentioned desirable characteristics of the particular material of which this layer is formed, but the air spaces are not necessarily an essential feature unless the material composing this layer would not otherwise have the required characteristics in sufficient degree to enable it to properly perform its functions.

The result obtained by making the layer 11^b of the inner-lining next to the shoe of an easily penetrable material is to make this layer act as a retainer for the small hard objects which may get into it. The air spaces illustrated in the layer 11^b also may act as retainers for small hard objects and therefore perform an equivalent function to the material of this layer being made of an easily penetrable material. They, therefore, are a mechanical means of obtaining or increasing the desired qualities of this layer.

The air spaces may be varied in number, form, size and location without departing from the spirit of my invention.

In Fig. 1, the layer 11^b is shown extending down to the points 18 and 19, and the layer 12^b to the points 20 and 21. The lower portion of the layer 12^b is shown as covered by flaps of fabric or other material 29 and 30 which may be a part of or attached to the shoe proper. The object of the flaps 29 and 30 is to assist in holding the inner-lining in place and to cover over the lower edges of the layer 12^b. The layer 12^b, not being attached to the shoe or the flaps, is free to move to compensate for any change in the size of the shoe or the proportion of the layer 11^b. The construction shown in Figs. 5 and 6 constitutes only one means which may be employed for incorporating my improved inner-lining as an integral part of the shoe and therefore I do not wish to be limited to the specific design illustrated. Other methods will readily suggest themselves to a person skilled in the art of designing or manufacturing tires.

It will be noted that the inner-lining does not have its lower edges joined together, or in other words, it does not form an inclosed tube. This is very essential in that it provides an opening for the insertion and removal of the inner-tube. It also allows the layer 12^b, which is not rigidly attached to the shoe, to expand around an increasing circumference as the tire is inflated, or enlarges through use, or the easily penetrable layer 11^b compresses. If it is desired to rigidly attach the lower edges or portions of the layer 12^b to the shoe, provision for expansion around an increasing circumference may be made by a fold in the layer, or by other equivalent means. The layers are thus enabled to come to a proper bearing and to take their proper share of strain as they automatically compensate for varying di-

mensions in a particular tire or for variation in sizes in different tires. If the innermost layer formed an inclosed tube or if its edges were rigidly attached to the shoe with 5 no provision for expanding around an increased circumference, then, being a tough, strong material with little elasticity, it would not be able to compensate for the variations in the sizes of different tires as 10 manufactured or for enlargement of the tires through use or for compression of the easily penetrable layer, and under these conditions it would be subject to excessive strain and possible rupture from the expansive force of the gas in the inner-tube, besides giving rise to other objectionable conditions such as too great a tendency of the inner-lining to creep, due to too loose a fit.

In the constructions hereinbefore described, I have shown the inner-lining as formed of two separate layers of material. It is of course evident that the inner-lining might be a composite structure which would have the inner and outer portions possessing 25 the required different characteristics. For instance, it might be woven, somewhat similar to a carpet with a deep nap. The nap being on the side toward the inner surface of the shoe, would perform the functions 30 of the pliable, easily penetrable layer 11^b and the back or base of the carpet would perform the functions of the tough, strong, penetration-resisting layer. I have mentioned the fact that the inner lining should 35 be of appreciable thickness. In practice, it may be anywhere from about one-eighth to about three-quarters of an inch thick, the thickness varying with the size of the tire and other considerations.

40 I am aware that manufacturers and inventors have recognized the advisability of increasing the thickness of the tread of tires in order to space the inner-tube farther from the danger zone of punctures but their 45 devices have lacked the novel form of construction herein described and do not successfully perform all of the desirable functions of my improved inner lining. Thickening the shoe 10 beyond a certain limit is 50 objectionable because it makes the shoe too stiff and gives rise to other undesirable conditions. My improved construction provides 55 desirable means for increasing the thickness of the tire tread without proportionately adding to the stiffness of the tire with the resulting increased strain and wear of the shoe under the bending action of the tire in use. The introduction of the pliable, soft layer between the shoe and the tough layer, 60 permits some relative motion between the three with the result that the combination is not as stiff or rigid as if it were an integral mass.

I am also aware that an inner lining of 65 canvas or other similar material has been

used to strengthen a shoe, but it does not perform its functions as desirable or in the same manner as my improved combination of the layers herein described.

When I refer to the layer 11^b as "easily penetrated", I mean that it shall be less difficult to penetrate than is the mass of rubber composition employed in the ordinary shoe 10 of the tire, and that its qualities would be such that it would be more difficult for a 75 small hard object to work its way from this layer into the layer 12^b, during the use of the tire, than it would be from the shoe 10 into the layer 12^b were the easily-penetrated layer omitted. 80

By the term "pliable" as applied to the layer of easily penetrable material, I mean that it offers less resistance to bending or distortion than does the mass of the shoe, and by describing the layer 12^b as a penetration resisting layer, I mean that it shall be more difficult to penetrate than is the layer 11^b. 85

By describing the layer of pliable, easily penetrable material as being "thick", I 90 merely mean that it is thick as compared to the layer 12^b and is capable of receiving such comparatively small hard objects as may work their way through the shoe.

By defining the layer 12^b as "non-stretchable", I mean that it does not stretch under the normal conditions of use and that such stretching as may take place is negligible and does not affect or modify the results sought, it being understood that practically 100 all materials are stretchable to a greater or less extent under certain conditions. 95

The details of the shoe and inner tube form no portion of my present invention and may therefore be varied greatly in detail. The canvas or other strength-giving element of the shoe may be replaced by cords, wires, or any other equivalent materials, all of which I include by the term "Fabric". 110

Having thus described my invention, what I claim as new and desire to secure by Letters Patent is:

1. An inner lining for use between the inner tube and the casing of a pneumatic tire, including a layer of pliable, rubber composition molded with voids or air-spaces in the inner and outer faces thereof and adapted to lie in direct contact with the inner surfaces of the casing, and a layer of tough, strong, penetration-resisting canvas between said composition and the inner tube and secured to said composition and carrying the latter. 115

2. A pneumatic tire including an outer casing of substantially non-stretchable construction, an inner tube of elastic material, an interposed layer of thick, pliable composition molded with voids or air-spaces in the inner and outer surfaces thereof, and a 120

125

- layer of tough, strong, substantially non-stretchable, penetration-resisting material between said first mentioned layer and said inner tube, the first mentioned layer serving 5 to permit relative bending movement of the casing and said second mentioned layer, the voids or air-spaces serving to make said first mentioned layer more pliable and also serving to receive and retain small hard objects 10 which may work their way through the casing, said first mentioned layer also serving to space the inner tube at a greater distance from the wearing surface of the tire, the

opposite side edges of said second mentioned layer being unattached to each other or to 15 the shoe, whereby said second mentioned layer may move in respect to the casing and assist in resisting the expansive force of the compressed gas in the inner tube.

Signed at New York, in the county of 20 New York, and State of New York, this 3d day of November, A. D. 1915.
